UNITED STATES PATENT OFFICE.

HENRY G. WURM, OF GLEN RIDGE, NEW JERSEY, ASSIGNOR TO R. NEUMANN & COMPANY, OF HOBOKEN, NEW JERSEY, A CORPORATION OF NEW JERSEY.

DESIGN FOR LEATHER OR SIMILAR ARTICLE.

Application filed October 16, 1928. Serial No. 28,508. Term of patent 14 years.

To all whom it may concern:

Be it known that I, HENRY G. WURM, a citizen of the United States, residing in Glen Ridge, county of Essex, State of New Jersey, have invented a new, original, and ornamental Design for Leather or Similar Article, of which the following is a specification, reference being had to the accompanying drawing, forming a part thereof.

The drawing is a face view of a piece of leather showing the design, a repeat unit of which consists of a series of eighteen blocks

I claim:

The ornamental design for leather or similar article substantially as shown and described.

HENRY G. WURM.
